UNITED STATES PATENT OFFICE.

MATTHEW L. TIPPIT, OF OLNEY, ILLINOIS.

TOWLINE.

Application filed May 10, 1924. Serial No. 712,315.

To all whom it may concern:

Be it known that I, MATTHEW L. TIPPIT, a citizen of the United States, residing at Olney, in the county of Richland and State of Illinois, have invented new and useful Improvements in Towlines, of which the following is a specification.

This invention relates to tow lines.

The object is to provide a line to be used particularly in towing automobiles or other vehicles, which is foldable into compact form when not in use, and capable of being easily and quickly unfolded and applied at one end to the towing car and at the other end to the stalled or crippled car.

Another object is to provide at each end of the tow line, fastening means which is permanently secured to said cable so as to avoid losing any of the parts and adapted to be passed around the axles or portions of the frames of the cars and so connected as to avoid accidental detachment when the cable is slack.

A final object is to provide means on the cable for preventing the same from marring the paint on the car when strain is brought to bear thereon.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:—

Figure 1 is a view showing portions of two automobiles connected by the improved tow line, one car being in the act of towing the other.

Figure 2 is a side elevation, on a larger scale, of one end of the tow line, with the connecting or attaching means in locked or closed position.

Figure 3 is a longitudinal section through the same.

Figure 4 is a transverse section taken on the line 4—4 of Figure 2.

Figure 5 is a perspective view of the connector in open or unlocked position.

The improved tow line comprises a piece of steel cable 1 of sufficient length to permit of the proper manipulation of the towing car and the towed car, and of a diameter to give the required strength, and yet permit of the line being coiled or folded into a small compass for carrying the same in the car. Each end of the cable is provided with the same form of fastening means, and a description of one will suffice for both, it being understood that either end of the tow line may be secured to either of the cars.

Each end of the cable is suitably formed into a closed loop 2, having the ends of the strands spliced into the cable proper in a well known manner, or bound thereto by wrapping wire, as shown in the drawing, the said loops 2 being engaged in the eyes 3 of hooks 4, which are preferably formed of wrought iron, or some other equally strong metal, so as to withstand the strain imparted thereto during the operation of pulling a car out of the mud and in towing the same.

The hooks are provided with somewhat restricted entrance openings 5, though of a size to freely pass over the cable 1 and admit the same to the hooks.

A relatively short piece of rubber tubing 6 surrounds the cable adjacent to each end thereof where joined to the hooks, said tubing being placed thereon prior to the connection to said hooks. The internal diameter of the tubing is preferably larger than the diameter of the cable, and is freely slidable thereon, so that one end may be moved into contact with the aforesaid loop 2 when the device is in use, and the slidability due to the difference in diameters permits the tubing to be rotated on the cable in order that a new surface may be presented to the point of wear, in a manner to be explained. The tubing may consist of a length of ordinary hose having the usual fabric foundation which tends to resist too great compression and cutting through the rubber by contact with the axle or other parts of a car.

In using the device, one end portion having the tubing 6 surrounding the same, is formed into a loop 7, as clearly shown in Figures 2 and 3, and hooked or passed around the rear axle 8 of a towing car, as shown at the right hand of Figure 1, the adjacent portion of the cable 1 being passed

through the relatively narrow entrance or folded into a small space for carrying in opening 5, which is too small to be thus passed over the tubing. By moving the hook longitudinally of the cable, from the dotted line position to the full line position shown in Figure 2, the hook is forced over the end of the tubing and locked thereto against accidental displacement, the external diameter of said tubing being such as to frictionally engage the interior of the hook for this purpose.

When the other end of the cable is similarly formed and connected to the front axle 9 of a car requiring to be towed, and the hook pressed back to engage with the tubing, the two ends are attached securely in place, and the operation of towing may be proceeded with without danger of the connection becoming loosened when the cable slacks, and without damaging the axles by reason of the rubber tubing. In removing the towing line from the cars, it is only necessary to swing the hooks away from the ends of the tubing, and to pass the same over the adjacent cable, in an obvious manner.

From the foregoing it will be seen that a simple, cheaply manufactured and strong and durable tow line has been provided, which is especially adapted for use in connection with automobiles, and which may be easily and quickly applied to or detached from the same, that the danger of becoming accidentally loosened has been eliminated, and that the device may be readily coiled

What is claimed is:—

1. A tow line for automobiles or the like comprising a length of cable having each end formed into a permanent loop, a hook having an eye loosely connected to each of the loops, each hook having an internal diameter greater than the diameter of the cable and provided with a restricted entrance opening capable of being freely passed over the cable, and a length of resilient tubing on each end of the cable in abutting relation to the terminal loops thereof, said tubing being rotatable on the cable and insertable endwise into the hook to frictionally engage the same.

2. A tow line comprising a length of cable having an end formed into a permanent loop, a hook loosely but permanently connected to the loop, the hook having an internal diameter greater than the diameter of the cable and provided with a restricted entrance opening capable of being freely passed over the cable, and a length of resilient tubing on the end of the cable in abutting relation to the permanent loop, said tubing being rotatable on the cable and insertable endwise into the hook to frictionally engage the same.

In testimony that I claim the foregoing as my own, I have hereto affixed my signature.

MATTHEW L. TIPPIT.
